US0D1105406S

(12) **United States Design Patent** (10) Patent No.: **US D1,105,406 S**
(45) Date of Patent: ** *Dec. 9, 2025

(54) **CEILING FAN BLADE IRON**

(71) Applicant: **Hunter Fan Company**, Memphis, TN (US)

(72) Inventor: **Benjamin Scotti Guthrie**, Germantown, TN (US)

(73) Assignee: **Hunter Fan Company**, Memphis, TN (US)

(*) Notice: This patent is subject to a terminal disclaimer.

(**) Term: **15 Years**

(21) Appl. No.: **29/875,276**

(22) Filed: **May 2, 2023**

Related U.S. Application Data

(60) Continuation of application No. 29/767,254, filed on Jan. 21, 2021, now Pat. No. Des. 989,940, which is a continuation of application No. 29/709,108, filed on Oct. 11, 2019, now Pat. No. Des. 911,510, which is a continuation of application No. 29/664,864, filed on Sep. 28, 2018, now Pat. No. Des. 867,573, which is a continuation of application No. 29/617,539, filed on Sep. 14, 2017, now abandoned, which is a division of application No. 29/557,369, filed on Mar. 8, 2016, now Pat. No. Des. 805,174.

CLAIM

The ornamental design for a ceiling fan blade iron as shown and described.

DESCRIPTION

FIG. 1 is a top perspective view of a ceiling fan blade iron according to my new design in the environment of a ceiling fan;

FIG. 2 is a bottom perspective view thereof;

FIG. 3 is an enlarged view of the blade iron in FIG. 2;

FIG. 4 is a top view of the blade iron in FIG. 1;

FIG. 5 is a bottom view of the blade iron in FIG. 1; and,

FIG. 6 is a front side view of the blade iron in FIG. 1.

The dash-dash broken lines illustrate portions of the ceiling fan that form no part of the claimed design. The dot-dot-dash broken lines surrounding the ceiling fan blade iron in FIG. 2 and FIG. 3 form no part of the claimed design.

1 Claim, 6 Drawing Sheets
